UNITED STATES PATENT OFFICE.

GEORGE FLETCHER HURT, OF ATLANTA, GEORGIA.

COKE BIN AND CHUTE.

No. 876,459.

Specification of Letters Patent.

Patented Jan. 14, 1908.

Application filed November 15, 1904. Serial No. 232,907.

To all whom it may concern:

Be it known that I, GEORGE FLETCHER HURT, a citizen of the United States, residing in Atlanta, in the county of Fulton, State of Georgia, have invented certain new and useful Improvements in Coke Bins and Chutes, of which the following is a specification.

This invention relates to coke bins and chutes and it has for an object to provide an improved construction of bin and chute by which the coke in passing from the bin, is cleared of all dust and other small particles.

Other objects and advantages will appear in the following description and will be more particularly pointed out in the appended claims.

In the drawings: Figure 1 is a vertical cross section of a portion of one of a series of bins and chutes. Fig. 2 is a section on the line 2—2, Fig. 1. Figs. 3, 4, and 5 are respectively top plan, side elevation, and a transverse section of an end of one of the bars forming a portion of the bottom of the bin, 25 and Fig. 6 is a partial side elevation of one of the bars forming the bottom of the chute.

Referring more particularly to the drawings, 7 and 7^a indicate the sloped or inclined converging bottom walls of the bin and 8 indicates the vertical side walls. Near the point where the converging bottom walls meet, one of them is provided with a series of slots 9 extending transversely to the slope completely across it. These slots gradually increase in width from their tops to their bottoms. The portion of the bottom provided with the slots, 9, is formed from a series of bars 10 of inverted cuneal cross section, having flat upper faces which comprise a relatively large part of the screening area of said bottom portion; and integral spacing members 11 at each end. These bars are arranged parallel on the beams of the bin with their flat upper faces in alinement, and abut one another at their ends, being held in place by two plates 12, each of which rests on one of the series of ends of the bars 10. The plates 12 are secured at several points throughout their length by bolts 13, which also pass through openings in some of the bars 10. The other inclined wall 7^a of the bottom of the bin, is provided with a sliding gate 14, operated in any suitable manner and controlling the discharge opening 15 of the bin.

Leading from the discharge opening is a chute 16, the bottom of which is in alinement with the slotted wall of the bin, of which it forms a continuation. This chute 16 has the greater portion of its bottom provided with slotted openings 17, transverse to the movement of the coke and like the slots 9 in the wall of the bin, formed by bars 18 which differ from the bars 10, only in being shorter and in having their ends provided with seats 19. The chute bars are held in place by strips 19^a.

Disposed below and common to the transverse slots in the chute 16 and in the wall 7, is a hopper 20, which delivers on a conveyer or other device 21, the dust and other fine dirt passing from the bin and chute. Coke is delivered into the bin and is discharged through the chute 16 into a vehicle of any kind, a charging buggy being shown in the drawings. The slots being transverse to the travel of the coke and extending over a portion of the bin on the inside of the gate and a portion of the chute on the outside of the gate, each piece of coke must pass over an opening, and in doing so, is caused to rotate and clear itself of all dust. Small particles of coke and other matter will also be separated from the larger coke, and, as the slots are smaller at their tops than at their bottoms, said separated matter will pass completely through the slots and not clog them.

The top surfaces of the bars all aline or are in the same inclined plane and therefore do not catch coke between them to impede the discharge of the other pieces. This construction, moreover, serves to reduce largely, the breakage of the coke in its passage over the grate bars. The bars are so shaped that spacing blocks are not required and as they rest upon beams of the bin and the series are held at each end by a single strip, repairs may be quickly and easily made.

The embodiment herein shown and described is for the purpose of illustration only and therefore I desire it to be understood that I may make any changes within the scope of the appended claim without departing from my invention.

Having thus described my invention, what I claim and desire to secure by Letters Patent is:

In a coke bin, the combination of two walls, having a discharge opening in one of said walls, the other of said walls comprising a plurality of parallel bars of inverted cuneal cross-section, extending transversely to the slope of the wall and having their broad up-

per surfaces in the same plane, spacing members on each end of each of the several bars and integral therewith in such manner as to form slots enlarging backwardly from the screen surface thus formed; a gate sliding within the first named wall for controlling the discharge of the coke; a transversely slotted chute disposed in the same inclined plane as the slotted wall and forming a con-

tinuation thereof; and a hopper common to 10 the slots in the bin wall and the chute.

The foregoing specification signed at Atlanta, Ga., this seventh day of Nov., 1904.

GEO. FLETCHER HURT.

In presence of—

J. B. JACOWAY,

Wm. H. FULTON.
